UNITED STATES PATENT OFFICE.

SAMUEL M. COFFMAN, OF KANSAS CITY, MISSOURI, AND GEORGE W. MOORE, OF PARSONS, KANSAS.

POWER ATTACHMENT FOR HAIR-CLIPPERS.

1,165,945.

Specification of Letters Patent.

Patented Dec. 28, 1915.

Application filed July 3, 1915. Serial No. 37,993.

To all whom it may concern:

Be it known that we, SAMUEL M. COFFMAN and GEORGE W. MOORE, citizens of the United States, residing, respectively, at 5 Kansas City and Parsons, in the counties of Jackson and Labette and States of Missouri and Kansas, have invented certain new and useful Improvements in Power Attachments for Hair-Clippers, of which the following is 10 a specification.

Our invention relates to hair clippers.

The object of the invention is to provide a power-driven hair clipper, the motor of which may be housed in the handle by 15 which the clipper is held and guided, the motor being so designed as not to materially increase the size of the handle.

A further object is to provide a motor hair clipper that may be driven through a 20 flexible shaft by a stationary motor if so desired instead of by the self-contained motor.

In order that the invention may be fully understood, reference will now be made to the accompanying drawing, in which:

25 Figure 1 is a side elevation of a clipper constructed according to the invention, a portion of the handle and of the clipper being broken away. Fig. 2 is a plan view, parts of the clipper being removed and the 30 handle in section. Fig. 3 shows a transverse section on line II—II of Fig. 1.

The head of the clipper is of the well known construction in general use, comprising a toothed knife 1 slidably mounted on a 35 coacting toothed knife 2, a bell-crank lever 3—4 on a stud 5 for actuating the knife 1; a tension spring 6, and adjusting nut 7. Knife 2 is provided with the usual handle 8.

9 designates a combined motor housing 40 and handle consisting of a tube which is closed at one end and open at the other. This tube is provided with a socket 10 for the reception of the end 11 of the clipper handle 8. For securing said handle permanently to the tube 9, we provide a metal strap 12, having its ends suitably secured to the tube, the strap holding the handle by friction or by a projection taking into a recess therein.

50 Fastened by screws 14 within the open end of the tube 9 is a block 15 which provides a bearing 16 for a transverse shaft 17, also a bearing 18 for the extreme inner end 19' of a motor shaft 19. Fixedly mounted 55 on shaft 17 is a worm wheel 20 having in-

tegral therewith a crank-wheel 21, provided with an eccentric pin 22. This pin is connected with a pitman 23 which is connected to the lever arm 3 by a pivot 24. 25 designates an electric motor, especially designed 60 to be contained by the handle 9. The motor shaft 19 is extended through the end of the handle, so that a flexible driving shaft may be coupled thereto. Fixedly mounted on the other end of the shaft 19 is a worm gear 65 26 which meshes with the worm wheel 20, the end 19' of the shaft being journaled in bearing 18.

A portion of the electric conducting cord is shown at 27. When the motor circuit is 70 closed the shaft 19 rotates, causing pitman 23 to oscillate lever 3—4 which in turn vibrates the knife 1.

For extra heavy work, or when the motor 75 25 is out of order, a stationary motor may be employed by connecting it with a flexible shaft to the projecting end of shaft 19.

It will be noted that the style of motor driven clipper herein shown is especially 80 adapted for barbers' use.

Having thus described our invention, what we claim and desire to secure by Letters Patent, is:

1. In combination with a clipper having a handle, a hollow handle closed at one end 85 and having its other end open, a socket adjacent the closed end of the handle, said handle being formed so as to be longitudinally engaged with said clipper handle and to receive the outer end of the clipper 90 handle in its said socket, a strap engaged over the inner end part of the clipper handle and secured to the hollow handle, and a motor in the hollow handle having means extending through the open end of the same 95 to drive the clipper.

2. In combination with a clipper having a handle, a hollow handle closed at one end and having its other end open, a socket adjacent the closed end of the handle, said handle being formed so as to be longitudinally engaged with said clipper handle and to receive the outer end of the clipper handle in its said socket, means to secure the clipper handle to the hollow handle at a point 100 in spaced relation to the socket, and a motor in the hollow handle having means extending through the open end of the same to drive the clipper.

3. In combination with a clipper and a 110

- hollow handle secured to the clipper, a member secured in the open end of the handle and formed with a bearing extending transverse of the handle, a shaft in said bearing
- 5 having a worm wheel thereon, said member further having a bearing extending longitudinally of the handle, a motor in the handle having a shaft one end of which is received in said longitudinal bearing, and having a
- 10 worm meshing with the worm wheel, a crank wheel connected to the worm wheel, and a pitman connected to the crank wheel and extending through the open end of the handle and connected to the clipper for
- 15 actuating the latter.
4. In combination with a clipper having

a handle, a hollow handle formed to be longitudinally engaged by said clipper handle, means to rigidly secure the clipper handle to the hollow handle, a motor in the hollow handle, and means connected to the motor and clipper and extending through the open end of the hollow handle to actuate the clipper.

In testimony whereof we affix our signatures, in the presence of two witnesses.

SAMUEL M. COFFMAN.
GEORGE W. MOORE.
